UNITED STATES PATENT OFFICE.

ALLEN DAVIS, JR., OF CINCINNATI, OHIO, ASSIGNOR TO THE CINO CHEMICAL PRODUCTS COMPANY, OF CINCINNATI, OHIO, A CORPORATION OF OHIO.

BOTTLE-SUPPORTING GASKET AND AIR FILTER.

Application filed February 10, 1927. Serial No. 167,266.

My invention relates to a process for sterilizing and maintaining beverages in sterile condition and to apparatus and a system with which beverages may be dispensed without deterioration.

It is the object of my invention to sterilize beverages such as are dispensed from cooling fountains and to maintain the beverages in non-fermenting condition during a much longer period than has heretofore been possible.

In the art the volume of business which is conducted particularly in warm weather in the dispensing of beverages such as orange drinks and the like is very great. The usual method of dispensing such beverages is for the soda fountain or shop to have a cooler into which a large bottle or container filled with the beverage to be dispensed is inserted in inverted position.

In the manufacture of orange drinks the manufacturer mixes certain percentages of oil of orange, sugar, citric acid and the like and ships the mixture in ordinary large bottles to the dispenser. The dispenser has usually a cooler which consists of a vessel having an open top with an ice compartment surrounding it. In order to discharge the content of the bottle into the cooler, the bottle is elevated and inserted in inverted position within the open top. A gasket is used for sealing the joint and as the seal of a tight gasket would prevent the release of the beverage from the bottle, it has been suggested that small notches be cut in the walls of the gasket to admit air.

With beverages which are handled in accordance with the above noted plan there is much loss due to rancidity of the liquids. I have found that in order to avoid any tendency toward rapid souring or rancidity that the beverage may be sterilized prior to being discharged into the fountain and then kept in a substantially sterile state by filtering the air which is admitted into the fountain to break the vacuum within the dispensing bottle.

I have shown in the drawings a preferred arrangement of dispensing apparatus with a novel sealing gasket embodying the principle of my invention.

In the drawings:

Figure 1 is a side elevation of a sealing gasket or ring equipped with air sterilizing ducts.

Figure 2 is a section along the lines 2—2 in Figure 1.

Figure 3 is a diagrammatic section of a dispensing fountain in operative condition.

Referring first to Figure 3 I have shown the bottle 1 having the sloping neck 2 which it will be noted, is shown in inverted position within the porcelain vessel 3. The discharge from the vessel is by means of a pipe 4 having a discharge valve 5 adjacent the end thereof. The vessel is retained within a chamber formed by side and bottom walls 6 and having semicircular lids 7 which are hinged as indicated at 8 so that ice may be inserted in the space surrounding the vessel.

The bottle is inserted into the opening in the vessel and a gasket or ring 9 having glass tubes 10 inserted in apertures therein, provides a substantial seal so that the contents of the bottle will not run over the cooler. The weight of the bottle is ordinarily sufficient to form a tight seal against the ring. Within the glass tubes I have inserted cotton, or wool fiber 11 or other suitable filtering means to sterilize the air which passes in through the glass tubes.

With such an arrangement as I have shown, with the beverage properly Pasteurized, I am able to keep the liquid from turning rancid or sour or fermenting for a substantially much longer time than has, to the best of my knowledge and belief, been possible heretofore.

There is a wide range of possibilities of accomplishing the same results by substitution of other filtering devices for sterilizing the air which is admitted to break the air seal. While I have shown a preferred arrangement in my novel gasket or sealing ring, I do not wish to be limited to the specific modification which I have described.

Having thus described my invention, what I claim as new and desire to secure by Letters Patent is:

1. A sealing device for the purposes described comprising an annular ring of elastic material, said ring having tubes therein with bacteria filtering fibrous material within the tubes.

2. A resilient gasket for sealing the joint between an inverted beverage bottle and a dispensing vessel, having passages therethrough with fibrous material disposed in the passages.

ALLEN DAVIS, JR.
